UNITED STATES PATENT OFFICE.

FRANK R. SMITH, OF TOMAH, WISCONSIN.

STUMP-EXTRACTOR.

SPECIFICATION forming part of Letters Patent No. 352,370, dated November 9, 1886.

Application filed June 8, 1886. Serial No. 201,496. (No model.)

To all whom it may concern:

Be it known that I, FRANK R. SMITH, a citizen of the United States, and a resident of Tomah, in the county of Monroe and State of Wisconsin, have invented certain new and useful Improvements in Stump Extractors; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a perspective view showing my 15 improved stump-extractor in position for operation. Fig. 2 is a top plan view of the same. Fig. 3 is a longitudinal vertical sectional view on line xx , Fig. 2. Fig. 4 is a perspective view of the standard or axle. Fig. 5 is a perspective view of the pulley for the drawing-rope, and Fig. 6 is an axial sectional view of the same.

Similar letters of reference indicate corresponding parts in all the figures.

My invention has relation to that class of 25 stump-extractors in which the winding-drum for the drawing-rope is journaled upon a standard or axle secured in a frame placed upon the ground and anchored to a stump or stake, and in which a sweep is secured to this wind- 30 ing-drum, and it contemplates certain im- 35 provements upon parts of the extractor for which Letters Patent No. 318,810 were granted to me on the 26th day of May, 1885; and it consists in the improved construction and combination of parts of the same, as hereinafter more fully described and claimed.

In the accompanying drawings, the letter A indicates the standard, which is cylindrical and provided with an annular flange, B, at its 40 lower end, and with an eccentric flange, C, at its upper end, the projecting portion of the said flange extending toward the anchoring-stump. The lower end of the standard is provided with a downwardly-extending flat portion, D, extending laterally toward the anchoring-stump, and the lower horizontal edge of this portion is provided with flanges E E, projecting to both sides, while the laterally-projecting portion of the flat portion of the standard is formed with a transverse perforation, F. Two beams, G G, are secured together by bolts H at their ends, the said bolts drawing the

beams toward the flat portion of the standard, clamping it, the beams being placed at both sides of the flat portion, and a bolt, I, passes 55 through the beams and through the perforation in the flat portion of the standard, furthermore securing the said standard. The ends of the beams projecting toward the anchoring-stump are formed with recesses J J 60 immediately inside of the connecting-bolt, the said recesses forming an aperture through which the anchoring-chain K may be passed and secured to the anchoring-stump L. A cross-beam, M, is bolted to the under side of 65 the ends of the beams, between which the standard is held, preventing the frame formed by the beams from being tilted. A drum, N, is journaled upon the standard, having an aperture of the same diameter as the eccentric 70 flange, so that the drum may be slipped over the said flange, and thereupon revolve upon the standard, the eccentric flange preventing the drum from being drawn up over the end of the standard when the rope is being wound 75 upon it. The outside of the drum is hour-glass-shaped, or contracted toward its middle, so that the rope may be wound upon the drum and continually be forced toward the middle of the drum, the rounded sides of 80 the drum allowing the rope to be wound upon the middle of the drum and preventing any chafing of the rope, as the rope will not come in contact with the said sides excepting by bearing directly against them. The 85 upper end of the drum is provided with the laterally-extending stud O and with the upwardly-projecting hook P, for the attachment of the sweep Q, similarly to the corresponding parts in my former patent, the sweep being 90 held to the stud by the link R, and the sweep is provided with the usual lead-pole. The drawing-rope T is secured at one end to the drum and at the other end to the end of the frame and passes over a sheave, U, in a block, 95 V, to which the chain W, which is attached to the tree or stump to be extracted, is secured. The fork or clevis X of this block is provided with a casing formed by two plates, Y Y, having flanges Z at their outer curved 100 edges, the said flanges projecting toward each other, and the inner edges of the plates are curved to follow the periphery of the sheave and project inside of the edges A' of the sheave,

the said curved edges of the plates being lettered B'.

It will be seen that by having the winding-drum shaped contracted at the middle the rope 5 will not chafe against any projecting flanges, as it will do in the majority of the stump-extractors of this construction, so that the rope may strike the drum at any angle from above the drum or from below, and it will at all 10 times be guided toward the middle of the drum without being chafed against flanges at the ends of the same.

The frame composed of the two beams and the cross-beam will allow the drum and its 15 standard to be secured to the anchoring stump or stake at a sufficient distance from the same to allow the sweep to be revolved without the necessity of cutting down the anchoring stump, and the cross-beam will prevent any 20 possibility of the frame being tilted, offering a wide support for the drum.

The flanged plates of the block for the drawing-rope will prevent the rope from slipping off from the sheave when the rope is slackened, and the sharpened edges of the plates, bearing inside of the edges of the sheave, will 25 prevent the rope from being cut by coming in contact with the edges of the sheave.

The entire device may be easily constructed 30 at a comparatively low cost, and may be easily repaired, if damaged, the extractor consisting of few and durable pieces.

It follows that the flanged upright and the drum contracted at the middle may be used 35 with other styles of stump-extractors and in different frames from the one herein described, and it also follows that the frame may be used with a different standard or drum. The sheave for the drawing-rope may also be used for different purposes and in different constructions 40 of stump-extractors.

Having thus described my invention, I claim and desire to secure by Letters Patent of the 45 United States—

1. In a stump-extractor, the combination of a vertical standard or axle having a flange, B, at its lower end, and having an eccentric circular flange at its upper end projecting toward the anchoring stump or stake, with a drum 50 having a bore of the same diameter as the eccentric flange and revolving upon the standard or axle, as and for the purpose shown and set forth.

2. In a stump-extractor, the combination of a vertical standard or axle having a flange at 55 its lower end, and having an eccentric flange at its upper end projecting toward the anchoring stump or stake, with a drum having a bore of the same diameter as the eccentric flange, 60 and revolving upon the standard and formed hour-glass-shaped, being contracted at its middle, as and for the purpose shown and set forth.

3. In a stump-extractor, the combination of a standard or axle having a flat portion extending from the lower end, and provided with 65 horizontal laterally-extending flanges at its lower edge, with two beams bolted at the sides

of the flat portion, clamping and holding the same, and a winding drum or pulley, as and for the purpose shown and set forth.

4. In a stump-extractor, the combination of a standard or axle having at its lower end a flat portion extending toward the anchoring stump or stake, and formed with a perforation in the extension and provided with laterally-projecting horizontal flanges at the lower edge, with two beams having bolts passing through them, and a bolt passing through them and through the perforation in the flat portion of the standard, clamping at both sides of the 80 said flat portion, and a winding drum or pulley, as and for the purpose shown and set forth.

5. In a stump-extractor, the combination of a standard for the winding-drum having a flat portion at its lower end extending toward the 85 anchor and provided with a transverse perforation in the said extended portion, and with laterally-projecting horizontal flanges at the lower edge, two beams clamping the flat portion between their ends, and having bolts passing through them and one bolt passing through the perforation in the flat portion of the standard, and formed with recesses in the inner sides of the ends, and an anchor-chain passed through the perforation formed by the recesses, 95 and a winding drum or pulley, as and for the purpose shown and set forth.

6. In a stump-extractor, the combination of a standard having a flange at its lower end and an eccentric circular flange at its upper 100 end, and having a flat portion extending toward the anchor, and formed with horizontal laterally-projecting flanges and with a transverse perforation in the extension, a winding-drum having a sweep adapted to turn 105 upon the standard, having a diameter equal to the diameter of the eccentric flange, two beams clamping the flat portion with their ends, and having connecting-bolts passing through them and through the perforated flat 110 portion, and formed with facing-recesses in the inner sides of the other ends, a cross-beam secured under the ends of the beams clamping the flat portion of the standard, and an anchor-chain passed through the aperture 115 formed by the recesses, as and for the purpose shown and set forth.

7. In a stump-extractor, the combination of a pulley-clevis, a sheave journaled in the said clevis, and two plates secured to the arms of the clevis, and having meeting curved flanges at their outer edges, and having the inner edges cut out concave and sharpened, fitting inside of the edges of the sheave, as and for the purpose shown and set forth.

In testimony that I claim the foregoing as my own I have hereunto affixed my signature in presence of two witnesses.

FRANK R. SMITH.
